UNITED STATES PATENT OFFICE.

FREDERICK J. ROSS AND WILLIAM H. ROSS, OF SOUTH HADLEY FALLS,
MASSACHUSETTS.

VELOCIPED-E-BOAT.

SPECIFICATION forming part of Letters Patent No. 380,221, dated March 27, 1888.

Application filed October 22, 1887. Serial No. 253,093. (No model.)

To all whom it may concern:

Be it known that we, FREDERICK J. ROSS and WILLIAM H. ROSS, of South Hadley Falls, in the county of Hampshire and Common-

wealth of Massachusetts, have invented a new and useful Improvement in Velocipede-Boats, of which the following is a specification, reference being had to the accompanying drawings, forming part thereof.

10 Our invention relates to that class of boats having two hulls or floats supporting between them a platform, upon which is located the crank pedal apparatus by means of which the propelling-wheel is operated, known as "velocipede" boats; and its object is to provide a boat of this nature which will be very simple and inexpensive in construction, and yet strong and capable of being driven at a high rate of speed, and in which provision is made 15 for propulsion of the boat by two or more persons at the same time.

To these ends our invention consists in the boat constructed as hereinafter fully described, and particularly pointed out in the 20 claims.

Referring to the drawings, in which like letters designate like parts in the several figures, Figure 1 is a plan view of the boat with the seats, seat-bar, and standards for the latter 25 removed. Fig. 2 is a side elevation of the boat complete. Fig. 3 is a vertical sectional view of one of the crank-shaft bearings, taken upon line $x-x$ in Fig. 1. Fig. 4 is a front view of one of the standards supporting the seat-bar. 30 Fig. 5 is a cross-section of one of the saddle-hangers. Fig. 6 is a front view of one of the seat-bar supporting-standards provided with a handle-bar and handles for use by lady riders. Fig. 7 is a side elevation of one of the saddle- 35 hangers and its saddle. 40

The letters A A designate the hulls, which may be made of paper, cedar, or other light wood, and are decked over throughout their length, as shown, to render them water-tight. 45 The hulls are connected together by two cross-bars, B B, suitably connected at each end to one of said hulls, and preferably by a third bar, C, which supports the steering-bar, as hereinafter described. The hulls are still fur- 50 ther united by the paddle-wheel shaft D, which

extends transversely across them near their rear ends, being journaled in bearings D', the particular construction of which will be presently described.

The letters E E designate two rails extending longitudinally between the hulls, and secured at each end to cross-bars B B, which rails support the power mechanism and the standards to which the seat-bar is secured. 55

As shown, the power mechanism consists of 6c two crank-shafts, F, mounted in uprights F', secured to the rails E, and having at each end a crank-arm, F², provided with a pedal, F³, whereby provision is made for the propulsion of the boat by two persons at the same time. 65 The bearings for said crank-shafts, and also the bearings D' for the wheel-shaft, will preferably be constructed as shown in Fig. 3, in which the uprights are shown as being provided with a bore to receive the shaft, which bore is screw-threaded throughout the greater portion of its length from its inner toward its outer end, and at its outer end is of slightly greater diameter. The shaft F is provided with two hubs, f, of a slightly less diameter 70 than the enlarged portions of the bores of the uprights in which said hubs are located, the inner faces of which are curved, as shown. Bushings f' are screwed into the bores of the 75 uprights from the side opposite the hubs on the shaft, said bushings having a bore of greater diameter than the diameter of the shaft between the hubs, and having their inner ends concaved, whereby a recess is formed between said bushings and the curved faces of hubs f, 80 to receive the balls f², which extend in a single row entirely around the shaft and entirely support it within the uprights. 85

The abutting surfaces of bushings f' and hubs f, as well as the balls f², will preferably 90 be case-hardened, so that the wear between said parts will be slight; but provision is made for taking up such wear by turning the bushing to advance it within the upright, a check-nut, f⁴, being located upon the bushing between the head of the latter and the upright, by means of which the bushing can be locked in its adjusted position. A very simple and cheap ball-bearing is thus afforded, by means of which 95 friction on the crank and wheel-shafts is re- 100

duced to a minimum, said shafts being supported laterally with respect to the hulls A A, as well as vertically, by the balls f^2 .

Midway between the rails E E each of the 5 crank-shafts is provided with a sprocket-wheel, F⁴, which wheels are preferably of the same diameter, and upon the wheel-shaft, in alignment with said wheels F⁴, is a third sprocket-wheel, D², preferably of one-half the 10 diameter of said wheels. A chain belt, G, having links of the proper size to receive the teeth on said wheels, passes around the front wheel F⁴ and wheel D² and over and beneath the rear wheel F⁴, whereby motion is transmitted from both wheels F⁴ to wheel D² and the wheel-shaft, said latter shaft making two revolutions to each revolution of the crank-shafts.

The standards which support the seat-bar 20 are preferably made from metal tubing, and consist of a main stem, H, having two outwardly and downwardly curved arms, H', which are provided at their lower ends with feet h, in each of which is a groove to receive one of 25 the rails E. The arms H' are also provided with downwardly-projecting bolts h', which extend through slots e in the rails E, and receive beneath said rails nuts h'. The slots e in the rails are located immediately in front 30 and rear of the bearings for the crank-shafts, and by loosening the nuts h' the standards can be adjusted toward and away from said crank-shafts to suit the convenience of the riders. In order to provide for vertical adjustment of 35 the seat-bar, we prefer to make the main stem H of the standards in two parts, one sliding within the other, as shown in Figs. 2, 4, and 6, and to provide the lower member with a set-screw, h³, by means of which the upper member 40 can be secured in different positions within said lower member. The seat-bar I is secured in any convenient manner upon the upper ends of the upper members of the standards.

The saddle-hangers K consist of upwardly-45 curved plates secured to the seat-bar by bolts k, passing through said plates and bar, and nuts k', turned on said bolts beneath the bar, as shown, or in any other convenient manner. Said hangers are provided at each end with an 50 ear, k², in each of which is pivoted a loop, k³, as shown in Figs. 5 and 7. The saddles L preferably have their front end extended to form a strap, L', and have secured to their lower side, near their rear end, a strap, L², one of 55 which straps is provided with a buckle at its free end and the other with holes to receive the tongue of said buckle, as shown. By passing strap L' through the front loop, k³, and strap L² through the rear loop, as shown in Fig. 7, 60 and connecting the ends of the straps together by means of the buckle, the saddle is suspended within the hanger in such manner as to yield to the movements of the rider when operating the pedal-cranks and afford an easy seat. The 65 saddle can be made more or less rigid with respect to the hanger by tightening or loosen-

ing the straps L' L². A handle-bar, M, secured to the seat-bar in front of the rear saddle, enables the rear rider to steady himself in his seat, while the front rider grasps a 70 similar handle-bar secured to the top of the steering-rod N and steers the boat. The steering-rod N near its upper end rests in an open bearing in the front end of the seat-bar, and at its lower end is rigidly secured to a bar, 75 N', midway between the ends of the latter. Said bar N' is centrally pivoted upon cross-bar C, and has secured to each end one end of the cord or rope N², which passes around the grooved pulleys N³ at the top of the tiller-80 posts of the rudders N', at the end of the hulls, as shown in Fig. 1. It will be obvious without further description that axial movement of rod N by means of its handle-bar will turn both rudders in one or the other direction to 85 change the course of the boat. As thus far described the boat is adapted for use by male riders only; but it can be quickly changed, so that a lady can occupy the front seat while a 90 gentleman sits behind and propels the boat, 95 by removing the seat-bar, securing the saddle-hangers directly to the top of the standards H, and removing the front standard to the rear of the front crank-shaft, slots e' being made in the rails E E at that point for this 100 purpose. When this is done, we prefer to provide each of the standards with a handle-bar, H', as shown in Fig. 6, secured to the main stem of the standard by means of a collar surrounding the same and having upwardly-105 curved arms, whereby a support is afforded upon either side of the saddle. A foot-rest will also be secured to the front cross-bar, B, as indicated by broken lines in Fig. 2, which will also serve as a support for the steering-rod in lieu of the seat-bar.

The wheel-shaft D is preferably tubular in form, and has secured to each end thereof a paddle-wheel, D³, composed of the hubs d, spokes d', and blades d'', the spokes being 110 braced by a wire, d', which may be continuous around the wheel, as shown, or composed of separate sections between each pair of spokes. A very light but strong wheel is thus afforded, and the combined operation of said wheels, 115 which make two revolutions to one of the crank-shafts, enables the boat to be driven at high speed with but little exertion on the part of the riders.

The boat thus constructed can be made very 120 cheaply and yet answer all the purposes of similar boats heretofore made, which are much more complicated and expensive in structure.

We do not wish to limit ourselves to the use 125 of two crank-shafts, as the number that could be employed in addition to the two shown is limited only by the size of the boat. It is obvious, also, that other modifications in the details of construction shown and described could be made without departing from the 130 spirit of our invention.

Having thus fully described our invention,

what we claim, and desire to secure by Letters Patent, is—

1. A velocipede-boat consisting of the hulls A A, a frame connecting one of said hulls with the other, a plurality of pedal-crank shafts mounted in bearings upon said frame, seats secured upon said frame adjacent to said shafts, a shaft having a paddle-wheel secured to each of its ends mounted in bearings upon said hulls, belt-connections between each of said crank-shafts and said wheel-shaft, rudders secured to said hulls, a steering-lever located in front of the first crank-shaft, and intermediate connections between said lever and both of said rudders, substantially as described, whereby said rudders can be operated in unison from the lever, substantially as set forth.
2. In a velocipede-boat, the combination, with hulls A A, having paddle-wheel shaft D, mounted in bearings thereon, of cross-bars B B, rails E E, extending between said bars, two or more pedal-crank shafts mounted in bearings upon said rails, standards H, adjustably secured to said rails, bar I, connected at each end to one of said standards, saddles L, mounted upon said bar I, sprocket-wheels secured to each of the crank-shafts and to the wheel-shaft, and belt G, connecting all of said sprocket-wheels together, substantially as set forth.
3. In the velocipede-boat herein described, the combination, with seat-bar I, supported substantially in the manner set forth, of the bow-shaped hangers K, secured to said bar, said hangers having the loops k³ at their ends, and saddles L, having the straps L' L², whereby they are adapted to be suspended between the loops on said hangers, substantially as described.
4. The combination, with the hulls A A, of

bar N', pivoted centrally between said hulls, 40 rod N, secured at one end to said bar, rudders N⁴, having grooved pulleys N³, secured to their tiller-posts, and cord or rope N², secured at each end to opposite ends of bar N', and passing around each of said pulleys, substantially as 45 and for the purpose described.

5. In the velocipede-boat herein described, the combination, with hulls A A, having the intermediate connecting-frame composed of bars B and rails E, of uprights F', secured to 50 said rails, each of said uprights containing a bore of greater diameter at one end than at the other, and screw-threaded throughout the portion of lesser diameter, shafts F, having hubs thereon, the surface of one side of which is 55 curved, as shown, bushings f', screwed into the bore of said uprights and having their inner ends concaved, and balls f², located between the ends of said bushings and the curved surfaces of the hubs on the shafts, arranged and 60 operating substantially as and for the purpose set forth.

6. The combination, with hulls A A, cross-bars B B, and rails E E, having slots e therein, of standards H, composed of two members, one 65 of which is vertically adjustable within the other, and having the curved arms H', secured to rails E by bolts passing through the slots in the latter, and seat-bar I, secured to the upper members of said standards, substantially as described, whereby provision is made for adjusting said seat-bar both vertically and longitudinally, for the purpose set forth.
